UNITED STATES PATENT OFFICE.

CHARLES W. MANZEL, OF BUFFALO, NEW YORK, ASSIGNOR TO MANZEL BROTHERS, OF BUFFALO, NEW YORK.

FORCE-FEED LUBRICATOR.

No. 820,979.

Specification of Letters Patent.

Patented May 22, 1906.

Application filed June 22, 1904. Serial No. 213,640.

To all whom it may concern:

Be it known that I, CHARLES W. MANZEL, a citizen of the United States, residing at Buffalo, in the county of Erie and State of New York, have invented certain new and useful Improvements in Force-Feed Lubricators, of which the following is a specification.

This invention relates to an improved force-feed lubricator.

One of the features of the invention has reference to an agitating device located directly within the oil-cup and which is designed principally for stirring a combined lubricating mixture of oil and graphite to prevent the graphite from settling.

Another feature has reference to a plurality of force-feed devices which are driven by a single cam.

The invention also has reference to the mechanism for operating the agitating device and to various details of construction, all of which will be fully and clearly hereinafter described and claimed; reference being had to the accompanying drawings, in which a preferred adaptation is shown.

Figure 1 represents a vertical section through the improved force-feed lubricator on line *a a*, Fig. 2. Fig. 2 is a top plan view of the improved lubricator. Fig. 3 is a detached side view of the cam-connecting arm looking in the direction of the arrow *V*, Fig. 4. Fig. 4 is a detached edge view of the cam-connecting arm looking in the direction of the arrow *W*, Fig. 3. Figs. 5, 6, and 7 are detached views of the spiral agitator. Fig. 8 is a section through the oil-cup to illustrate the construction of the mechanism mounted thereon and contained therein. Fig. 9 is a detached top plan view of the top cap or cover of the oil-cup. Fig. 10 is a detached side elevation of the gear-frame. Fig. 11 is a detached front view of one of the casings fitted over the openings in the top cap of the oil-cup. Fig. 12 is a detached view of the tubular gear-wheel. Fig. 13 is a horizontal section through the driving mechanism on line *b b*, Fig. 1. Fig. 14 is a vertical section through the driving mechanism on line *c c*, Fig. 3. Fig. 15 is a transverse section on line *d d*, Fig. 13.

In referring to the accompanying drawings in the following explanation in detail of the adaptation of my invention shown therein like numerals designate like parts.

This improved lubricator is principally de-

signed to feed a mixture of oil and graphite, and in order to prevent the graphite from settling an agitating device is placed directly in the oil-cup itself, which is operated from the same shaft driving the force-feeding devices. 60

The oil-cup proper is composed of a cylinder of glass 1, a top cover or plate 2, and a bottom plate 3. The top has a central opening and a comparatively large semicircular opening on each side of said central opening, 65 in one of which a wire-gauze cage or strainer 4 is supported. The top and bottom plates 2 and 3 are provided with flanges 5 and 5^a, which fit around the margins of the ends of the cylinder, and a packing 6 is interposed 70 between each of the plates and the edges of the cylinder. (See Fig. 1.) The bottom plate has a central projecting portion 7, which is provided with a vertical recess or socket 8, which is interiorly screw-threaded. 75

The component parts of the oil-cup proper are secured together by a rod 9, the lower end of which screws into the screw-threaded depression 8 in the bottom plate 3 and the upper portion of which passes through the central opening in the top plate 2 and is screw-threaded at its projecting end, as shown at 10 in Fig. 1, to receive the lock-cap 11, which screws upon said end 10.

The bottom plate 3 has a tubular member 85 which may be formed or cast integral with it, as shown in the accompanying drawings, or formed separate and attached thereto in any well-known way. This tubular member has an opening, which is divided into a feeding- 90 chamber and a valve-chamber, said chambers being separated by an opening of lesser or reduced diameter.

In the adaptation shown in the accompanying drawings the tubular member is 95 cast integral with the bottom plate and forms an enlargement 12, projecting from the bottom of the plate, and said enlargement is extended laterally from one side of the bottom plate to provide a horizontally-projecting 100 continuation 13 of the tubular member.

The horizontal opening which extends through the tubular member of the bottom plate is divided into a feeding-chamber 14, a valve-chamber 15, and a short opening 16 of reduced diameter intermediate the feeding-chamber and the valve-chamber. A vertical opening 17 extends through the wall of the bottom plate on one side of the center and forms a passage-way for oil from the oil- 110

cup into the feeding-chamber and is sufficiently large to permit the oil to flow freely, as shown in Fig. 1. A feeding piston-rod 18 is slidably arranged in the feeding-chamber 5 and projects through the continuation 13 of the tubular member, being reciprocated in a manner hereinafter set forth. The opening in the outer extremity of the horizontal extension is enlarged to form a packing-chamber 10, in which a packing 19 of suitable material is placed and compressed by a screw-nut 20. (See Fig. 1.)

The valve arranged in the valve-chamber 15 is automatic in action and is preferably of 15 the reciprocating block type, as shown in Fig. 1. In this form the adjacent annular wall formed by the reduction of the valve-chamber 15 into the intermediate chamber or opening 16 is formed to constitute a valve-seat 20 for a valve-block 21, which is located in the valve-chamber 15 and has a tapered end which is normally held in contact with said seat by a spiral spring 22. The greater portion of the spring 22 loosely encircles the 25 reduced stem 23 of the valve-block, and a screw 24, which screws into the inner extremity of the tubular member, is hollow nearly throughout its length to form a socket 25, in which the spring and the stem of the 30 valve-block are housed. The tension of the spring can be regulated by longitudinal adjustment of the screw, and the end of the screw by striking against the chamber edge 35 constitutes a stop to limit the movement of the valve-block 21 and prevent excessive compression of the spring 22. (See Fig. 1.) The tubular member is provided with a downwardly-extending part 26, which has a vertical opening 27 extending therethrough and 40 communicating with the valve-chamber 15.

The oil-cup and its feeding mechanism are mounted upon a frame which is provided with a sight-glass, into which the oil is forced by the feeding mechanism and a second feeding mechanism for drawing oil from the sight-glass and forcing it to the point desired.

Hereafter, the oil-feeding mechanism arranged between the oil-cup and sight-glass will be designated as the "upper" feeding mechanism, its piston-rod 18, the upper piston-rod, and the automatic valve located in the valve-chamber 15, the upper horizontal valve to distinguish them from other and substantially similar mechanisms, to be herein- 55 after described.

The frame upon which the oil-cup is supported is formed substantially like the frame shown in my Patent No. 635,694, granted October 24, 1899, and has a vertical portion 60 or member 28, provided with a vertical opening 29, in which the sight-glass 30 is supported. The lower portion of the opening is reduced in size, as shown in Fig. 1, and a ball-valve device is vertically arranged therein. 65 This ball-valve device, which I will herein-

after designate as the "intermediate" vertical valve, is composed of a valve-casing 31, having an annular valve-seat 32 near its upper end, a ball 33, arranged in the casing and adapted to engage with the seat 32 to close 70 the passage, and a spiral spring 34, arranged to normally maintain the ball in contact with the seat with a spring tension. Below the vertical portion or member 28 is a horizontal tubular portion or member 35, which has a 75 horizontal opening extending through it and is divided into communicating chambers. One of these chambers 36 is directly below the vertical intermediate valve, with which it is connected by a short vertical opening 37 80 and constitutes an oil-feeding chamber for a lower feeding mechanism. To the right of the chamber 36 is located a valve-chamber 38, which is connected to the feeding-chamber by a short communicating opening or chamber 39 of reduced diameter. This valve-chamber is divided into a plurality of successively-enlarged sections in each of which a valve device is arranged.

The valve device in the first section comprises simply a ball 40 and a tension-spring 41 and that in the second section a valve-casing 42, which has an annular valve-seat 43, a ball 44, and a spring 45. The spring 45 is secured in place by a tubular nut 46, which 95 screws in the end of the horizontal portion 35. A piston-rod 47 has one end slidably mounted in the oil-feed chamber 36 and is reciprocated substantially as shown in my Patent No. 633,694 by means of a cam 48, in 100 which a crank-pin (shown in dotted lines in Fig. 1) extending from a disk 49 projects. The disk 49 is mounted at one end of a shaft 50, which is journaled in the frame, and a flanged disk 51 is mounted at or near the opposite end of the shaft, which is intermittently rotated by a ball-clutch 52, mounted on a vibratile arm or rod 53, and which in turn is vibrated by any well-known source of power—such, for instance, as a connecting-rod extending from an operating portion of 105 an engine. The disk 49 is rotated in only one direction by the clutch 52, being held stationary during the return movement of said clutch by a brake-clutch 54, which is similar 115 in construction to the clutch 52 and mounted upon an arm 55, clamped around the projecting portion 51 of the frame. (See Fig. 5.) The piston-rod 47, which I term the "lower" 120 piston-rod, is connected to the upper piston-rod 18 by a vertical cross-arm 56, so that the two piston-rods are simultaneously reciprocated. This cross-arm is formed integral with and projects vertically from the cam 48, substantially as shown in Fig. 1, 125 having an opening 57 near its lower end, through which the outer portion of the lower piston-rod 47 is fitted, and an upper bifurcated or forked extremity 58, the members 130 of which straddle the central reduced portion

59 of a screw-nut 60, which screws upon the outer screw-threaded portion 61 of the upper piston-rod and is locked in position by a knurled lock-nut 62. The object of this is to 5 provide for longitudinal adjustment of the upper piston-rod to regulate the oil-feed, the upper piston-rod being rotated by its enlarged knurled end 63 to screw it forward or back in the nut 60.

10 The object of the intermediate vertical valve between the lower feed-chamber 36 and the sight-glass is to prevent the oil charge in the lower feed-chamber 36 backing up into the sight-glass during the earlier portion of 15 the feeding movement of the lower piston-rod.

10 The top plate is provided with a short centrally-depend ing tube 64 and oppositely-extending strengthening-flanges 65 and 66, extending from said tube.

15 The frame may be provided with a socket 67 for attachment to a suitable support.

20 The agitating device which is arranged within the oil-cup, and the agitating portion 25 proper of which is wholly and directly in said oil-cup, comprises a sleeve 68 and a spiral agitating-strip 69, which encircles and is secured to arms projecting from the sleeve. The sleeve is rotatably mounted upon the 30 vertical rod 9, which thus performs a two-fold function, serving to secure the parts of the oil-cup together and acting as a support for the sleeve 68.

25 The spiral 69 is attached at its upper end 35 to an arm 70, extending laterally from the sleeve 68, and at its lower end to an arm 71, extending out from the sleeve and substantially vertically beneath the arm 70, so that the spiral completes one complete spiral turn 40 around the sleeve. The sleeve also has a depending portion 72, which extends on one side of the socket 8 to the top surface of the bottom plate 3, and a flat arm 73 extending horizontally out from the lower extremity of 45 the depending portion 72 and constitutes a scraper which prevents graphite collecting on and adhering to the bottom plate. The scraper 73 is connected at its outer end to the outer end of the lower arm 71 by a vertical 50 connection 74. The arms 70 and 71, depending portion 72, scraper 73, and connection 74 are all preferably cast integral with the sleeve 69. The sleeve is rotated by 55 means of gears which are supported in a gear-frame mounted on the top plate and are driven from the disk 51 in a manner to be hereinafter described.

60 The gear-frame consists of a horizontal bottom member 75, which is fastened to the top plate 2 by screws 76, two vertical members 77 and 78, which are united at the top by a collar or ring 79, and a horizontal tubular extension 80, projecting outwardly from the vertical member 77. The rod 9 is made 65 sufficiently long to project above the top

plate 2 and through the collar 79, with the lock-cap 11 screwing upon the upper extremity 10, extending above the collar 79 and against the top surface of the collar. A tubular bevel gear-wheel 81 is rotatably 70 mounted on the rod 9 above the top plate 2 and between the vertical frame members 77 and 78 and has a reduced depending tubular portion 82, which extends through the central opening in the top cover and interlocks 75 with the upper extremity of the sleeve 68. The interlocking is accomplished by cutting away substantially half of the top of the sleeve 68 for a short distance and likewise cutting away a similar half portion from the 80 lower end of the depending portion 82, so as to leave two semicircular projecting ends 83 and 84, which will extend past each other and lock, thereby preventing rotation of the sleeve 68 independent of the bevel gear- 85 wheel 81.

85 A horizontal shaft 85 is journaled in the horizontal frame extension 80 and has a bevel gear-wheel 86 mounted at its inner end, which meshes with the beveled gear-wheel 81. The horizontal shaft 85 is preferably connected to the disk 51, so that the spiral agitating device will be operated from the same power that actuates the force-feed devices. This is preferably accomplished by 90 fitting a peripheral groove-ring 87 around the disk 49 and connecting it to a similarly peripheral grooved pulley-wheel 88, mounted on the outer extremity of the horizontal shaft 85 by a belt 89.

95 The enlarged semicircular openings on each side of the central opening in the top plate are inclosed and covered by semicircular housings 90, which are secured by screws over each opening and have hinge top lids 91, 100 which may be readily thrown back to expose the opening and permit the cup to be readily filled.

105 The operation of this improved force-feed lubricator is as follows: The device being attached to a suitable mechanism or the like requiring lubrication and the vibratile arm connected to an operating device, oil and graphite are poured separately into the oil-cup through the separate semicircular openings in the top plate. The outward reciprocating movement of the upper piston-rod 18, withdrawing said piston into the position shown in Fig. 1, creates a partial vacuum in the feed-chamber 14, so that atmospheric 110 pressure combined with gravity forces a charge of oil from the oil-cup through the vertical opening 17 into the feed-chamber 14. The inward movement of the upper piston-rod 18 now forces the oil charge in the feed-chamber through the upper automatic valve 115 and the vertical opening 27 into the sight-glass 30. Another outward movement of the two pistons brings another charge into the upper feed-chamber 14, and the sight- 120

glass 30 being loosely set in the member 28, so that air has a chance to enter, the lower piston creates a partial vacuum in the lower feed-chamber 36, so that atmospheric pressure will force a charge of oil in the sight-glass through the intermediate vertical valve device into the lower feed-chamber 36. The air enters the sight-glass through the semi-circular depressions 92, which are formed in the bottom surface of the portion 26. (See Figs. 1 and 8.) The next inward movement of the two pistons forces the charge of oil in the upper feed-chamber into the sight-glass in the manner before described and the charge of oil in the lower feed-chamber to any desired lubricating-point. At the same time the intermittent rotation of the disk 51 imparts a like intermittent movement to the horizontal shaft 85 through the belt 89, and the horizontal shaft in turn imparts a like intermittent movement to the spiral agitating device through the bevel-gears 81 and 86.

I claim as my invention—

1. In a device of the class described, an oil-cup, a rod located in central vertical position in said oil-cup, an agitator arranged wholly within the cup and rotatably mounted on said rod, a bevel gear-wheel having a part interlocking with the agitator to rotate in unison therewith, a shaft having a bevel gear-wheel meshing with the first-mentioned bevel-gear, and means for rotating said shaft, substantially as set forth.

2. In a device of the class described, a plurality of force-feed devices, a shaft and a cam reciprocated by said shaft and having a vertical arm connected to the piston-rod of one of said force-feed devices and an enlargement through which another piston-rod passes.

CHARLES W. MANZEL.
